(57) **CLAIM**

The ornamental design for a bone plate, as shown and described.

DESCRIPTION

FIG. 1 shows a front, right perspective view of an embodiment of a bone plate;

FIG. 2 shows a front view thereof;

FIG. 3 shows a rear thereof;

FIG. 4 shows a left-side thereof;

FIG. 5 shows a right-side view thereof;

FIG. 6 shows a top end view thereof;

FIG. 7 shows a bottom end view thereof;

FIG. 8 shows a front, right perspective view of another embodiment of a bone plate;

FIG. 9 shows a front view thereof;

FIG. 10 shows a rear thereof;

FIG. 11 shows a left-side thereof;

FIG. 12 shows a right-side view thereof;

FIG. 13 shows a top end view thereof; and,

FIG. 14 shows a bottom end view thereof.

The broken lines illustrate environmental structure and form no part of the claimed design.

1 Claim, 12 Drawing Sheets
